Fig. 3

To all whom it may concern:

Be it known that I, Dorothy Stevens, a citizen of the United States, residing in the city of New York, Borough of Manhattan, county and State of New York, have invented a new, original, and ornamental Design for a Child's Sleeping Bag or Similar Article, of which the following is a specification, reference being had to the accompanying drawing, constituting a part hereof:

Fig. 1 is a plan view of a child's sleeping bag, showing my new design;

Fig. 2 is a side elevational view thereof; and

Fig. 3 is a perspective view of the same.

The bottom or underside of the child's sleeping bag shown in Fig. 1 is plain and unornamented.

I claim:

The ornamental design for a child's sleeping bag or similar article, substantially as shown and described.
